UNITED STATES PATENT OFFICE.

CHARLES T. SPRINGMAN, OF DETROIT, MICHIGAN, ASSIGNOR TO SPRINGMAN PAPER PRODUCTS COMPANY, OF DETROIT, MICHIGAN, A CORPORATION OF MICHIGAN.

EASEL.

1,132,629.

Specification of Letters Patent.

Patented Mar. 23, 1915.

Application filed May 6, 1914. Serial No. 836,592.

To all whom it may concern:

Be it known that I, CHARLES T. SPRINGMAN, a citizen of the United States, and a resident of Detroit, in the county of Wayne 5 and State of Michigan, have invented a new and useful Easel, of which the following is a specification.

This invention relates to means for holding cards, photographs, calendars and other 10 light articles in an upright position, and its object is to produce an easel which may be formed complete at a single stroke of a cutting die, which shall be self-locking, and which may be made at low cost.

15 This invention consists in the details of construction shown, described and particularly pointed out in the subjoined claims.

In the accompanying drawings, Figure 1 is a plan view of one form of the easel showing the parts in open position. Fig. 2 is a 20 rear view of a completed easel before being attached to a card or other article which it is to support. Fig. 3 is a side view of the easel shown in Fig. 2 attached to a card.

25 Fig. 4 is a fragmentary section on the line 4-4 of Fig. 3. Fig. 5 is a perspective view of a portion of a modified form of easel in which my invention is embodied. Fig. 6 is a side elevation of the easel shown in Fig. 5. 30 Fig. 7 is a plan of the brace shown in Figs. 5 and 6.

Similar reference characters refer to like parts throughout the several views.

In the embodiment shown in Figs. 1 to 3, 35 inclusive, 1 indicates a blank of straw-board, wood-veneer, or other suitable material cut through along the heavy lines, and scored along the light vertical lines 2 and the horizontal line 3 to form the front or supporting member 4, the struts or wings 5, the brace 6 and the tongues 7. The brace 6 is provided on each side thereof with an ear 8, in the upper surface of which is formed a dent or depression 9. The sides of the 40 tongues 7 may diverge from the brace, and the upper edge thereof is cut in each case in such manner as to leave the projection 11 integral with and extending downwardly from the corresponding strut or wing 5.

45 In use the struts or wings are bent backwardly from the card A to which the part 4 is cemented, along the lines 2, until they contact with the edges of the bent-down brace 6, each of the ears 8 being received in 50 the opening formed by bending the corre-

sponding tongue 7 outwardly. In this position, projections 11 are received in the depressions 9 in the ears 8, and the tongues 7 engage with the respective lower surface of the ears 8, pressing them against the projections 11, whereby withdrawal of the ears from engagement with the corresponding struts or wings is prevented.

The easel shown in Figs. 5, 6 and 7 comprises a front 12, a strut or wing 13 and a 60 brace 14, all cut from a single sheet of material, it being understood that the sheet may be scored along the lines 15 and 16 to allow bending of the parts into the relative position shown in Figs. 5 and 6. The brace is 65 hinged to the projection 17, which is a part of the front 12, and the said brace comprises a base 18 and a laterally projecting ear 20, having a depression 21 in its upper surface. This ear is adapted to be received in an 70 opening left by forcing a tongue 22, that corresponds in all respects to the tongues 7 heretofore described, laterally from the body of the strut 13, in which position the projection 23, corresponding to the projections 80 11, is received in the depression 21. A vertical section through this joint is exactly the same as the section shown in Fig. 4. It will be noticed that, when the brace is in the 85 position shown, that is, in locking engagement with the strut or wing 13, the edge of its base 18 is received beneath a shoulder 24 formed on the strut when the brace is severed therefrom. This shoulder, therefore, constitutes an intermediate support for the 90 brace, and renders the connection between the front and the strut more rigid than would otherwise be the case, and also prevents the brace from swinging up.

It is obvious that minor changes may be 95 made in the easel without departing from the spirit of my invention. I do not, therefore, desire to be limited otherwise than as indicated by the appended claims.

I claim:

1. An easel comprising a member adapted to be secured to the article to be supported, a strut on one side edge of the supporting member and bendable to a position at an angle thereto, a brace also on the supporting 105 member and bendable in respect thereto on a line at substantially right angles to the line on which the strut is bendable, a tongue on the strut, said strut having an opening resulting from the forming of the tongue, 110

100

105

110

a projection on the strut adapted to extend into said opening, a laterally extending ear on the brace adapted to be received in the opening in the strut, said ear having a depression therein to receive the projection, whereby disengagement of the strut and brace from each other is then prevented, said tongue holding the ear against said projection.

10 2. An easel comprising a supporting member adapted to be secured to a card, a strut on one side edge of the supporting member and bendable to a position at an angle thereto, a brace also on the supporting member 15 and bendable to extend transversely to the strut, a tongue struck from the strut and leaving an opening therethrough, said tongue having a base along which it is secured to the strut and one edge of the opening being opposite the said base, a projection on the strut adapted to extend into the opening from the edge opposite the base, a laterally projecting ear on the brace adapted to be received in the opening in the strut, 20 said ear having a depression in one face thereof to receive the projection on the strut, and said tongue then contacting with the opposite face of the ear, whereby disengagement of the strut and brace from each other 25 is then prevented.

3. An easel comprising a supporting member, a strut on one side edge of the supporting member and bendable to a position at an angle thereto, a brace also on the supporting 35 member and bendable in respect thereto about a base line at substantially right angles to the axis about which the strut is bendable, said strut having an opening therethrough, said brace comprising a base and a 40 laterally projecting ear, the latter of which is adapted to extend through the said opening in the strut, and a rigid shoulder on the inner edge of the strut adapted to engage with the brace at a point intermediate the 45 base and the ear.

4. An easel comprising a supporting member, a strut on one side edge of the support-

ing member and bendable to a position at an angle thereto, a brace also on the supporting member and bendable in respect thereto 50 about a base line at substantially right angles to the axis about which the strut is bendable, a tongue struck from the strut and leaving an opening therethrough, said tongue having a base along which it unites 55 with the strut and one edge of the opening being opposite the said base, a projection on the strut adapted to extend into the opening from the edge opposite the base, a laterally projecting ear on the brace adapted to be received in the opening in the strut, said ear having a depression in one face thereof in which the projection on the strut may be received, said tongue then contacting with the opposite face of the ear, whereby disengagement 60 of the strut and brace from each other is then prevented, and a shoulder on the strut adapted to engage with the brace at a point intermediate the base and the ear.

5. An article of manufacture, comprising 70 three portions, the first a sheet, the second another sheet on one side edge of the first mentioned sheet and bendable to a position at an angle thereto, the third a brace also on the first mentioned sheet and bendable in 75 respect thereto on a line at substantially right angles to the line on which the second portion is bendable, said second portion having an opening, a projection on the second portion adapted to extend into the opening, a laterally projecting ear on the brace adapted to be received in the opening in the second portion, said ear having a depression in one face thereof in which the projection may be received, whereby disengagement of 80 the second portion and the brace from each other is then prevented.

In testimony whereof I have signed this specification in the presence of two subscribing witnesses.

CHAS. T. SPRINGMAN.
